THERMIC SIPHON

Gust J. Christenson, Chicago, Ill., assignor to
Locomotive Firebox Company, Chicago, Ill., a
corporation of Delaware

Application June 20, 1935, Serial No. 27,560

19 Claims. (Cl. 122—68)

This invention relates to improvements in thermic siphons and it consists of the matters hereinafter described and more particularly pointed out in the appended claims.

5 The conventional type of thermic siphon as heretofore devised and which is now extensively used constitutes a flat hollow, single compartment water wall disposed in the firebox of a locomotive type of boiler. Such a siphon has its discharge 10 end opening preferably through the crown sheet of the firebox and has its inlet end opening through another sheet of the firebox at a point below the lowest flue thereof. The siphon materially increases the superficial area of the firebox 15 and also functions to increase the water steaming and circulating efficiency of the boiler, as a whole.

Ordinarily the inlet for the siphon is provided 20 by a relatively short, tubular inlet neck fixed at its end in a diaphragm in the front throat sheet, said neck joining the front bottom end of the body by an inside rounded corner. The top or 25 discharge end of the siphon body is usually provided with an attaching flange, welded into a suitable opening in the crown sheet.

25 In the heating up of the firebox, the crown sheet has a very definite upward movement and when the firebox cools down, the crown sheet has an opposite or downward movement. Neither of these movements can be restrained. In such movements of the crown sheet, the siphon moves therewith and due to the fact that the inlet neck anchors the siphon in the throat sheet, the stresses are largely localized at the points as provided by the inside corners previously mentioned.

30 When these stresses exceed the elastic limit of the metal at said inside corners, transverse fractures there occur.

One of the objects of the present invention is to provide a novel siphon structure permitting 35 the use of a relatively long neck, through which the expansion and contraction movement mentioned may be distributed without producing fractures because the force or stress required to flex the neck is reduced as the length of the neck is increased.

40 Another object of the invention is to provide a siphon structure so formed as to produce more heating surface therefor without increasing the size of the metallic plates required to make the 45 siphon and at the same time, make it practical to employ an inlet neck of such length as will provide the required flexibility.

45 A further object of the invention is to provide a siphon of such formation that the number of staybolts required is reduced with a saving in in-

stallation cost and this without sacrificing the safety factor.

Still another object of the invention is to provide a siphon of this kind including a body formed with a plurality of communicating compartments 5 all having a common outlet through the crown sheet and wherein said compartments draw water from different points of the boiler, thus insuring such water circulation throughout the entire boiler as will eliminate quiescent areas wherein 10 sediment may accumulate.

Still a further object of the invention is to provide a siphon of such design that it is practicable to employ a neck at least as long as the arch to be associated therewith, thus permitting the use 15 of a single pattern arch brick in each longitudinal row and at the same time providing a better and larger area of supporting engagement for the bricks forming the arch.

Again, it is an object of the invention to provide 20 a siphon of this kind including a body and a relatively long neck of seamless tubing which communicates with the body at a point forwardly of its rear end, thereby affording greater flexibility in the siphon, as a whole.

25 The above mentioned objects of the invention, as well as others, together with the many advantages thereof, will more fully appear as I proceed with my specification.

In the drawings:

Fig. 1 is a longitudinal vertical sectional view 30 through a combustion chamber type of locomotive firebox embodying the preferred form of the invention;

Fig. 2 is a transverse vertical sectional view 35 through a part of the firebox as taken on the line 2—2 of Fig. 1; and

Figs. 3, 4, 5 and 6 are detail sectional views 40 through parts of the improved siphon on an enlarged scale, as taken on the lines 3—3, 4—4, 5—5 and 6—6 respectively, of Fig. 1.

Referring now in detail to that embodiment of the invention, illustrated in the accompanying drawings, the firebox therein shown includes the crown sheet 5 which merges into the inner side 45 sheets 6, the inner back sheet 7 and inner throat sheet 8. The crown sheet extends forwardly of the inner throat sheet 8 to form the top of the combustion chamber 9. This chamber is closed at the front end by a flue sheet 10 and the bottom 50 11 of said chamber merges into the front end of the inner throat sheet 8.

The outer rear sheet is indicated at 12, the outer side sheets are indicated at 13 and the outer throat sheet is indicated at 14. Said sheets 55

cooperate with the top sheet and outer side sheets 13 in forming the back water leg 15, the side water legs 16 and the front throat 17 respectively, all in communication with the water space 18 of the boiler. The back and side water legs and the front throat are bottomed by a mud ring 19 and portions of the inner and outer back sheets are formed to coact in providing a fuel door opening 20.

In the firebox is provided one or more of the improved siphons indicated as a whole as at 21. In certain sizes of fireboxes, where only one siphon is employed, the siphon is disposed in the vertical median plane of the firebox. Where two 15 of such siphons are employed as illustrated herein, such siphons are disposed, one on each side of said vertical median plane of the firebox.

Each siphon as herein shown comprises a flat hollow body formed to provide front and rear, 20 relatively deep compartments or chambers 22-23 respectively, separated by an intermediate compartment 24 of less depth. The body includes laterally spaced side walls 25-25 and transversely rounded front and rear end walls 26 and 25 27 respectively. Said side and end walls are flared outwardly around the entire top end of the body, by means of inside curved corners 28 to merge into a laterally extending flange 28a. This flange is fitted and welded as at 29 in a suitable 30 longitudinal opening in the crown sheet. Thus the open top end of the siphon body provides a common discharge for all three compartments of the siphon body, into the water space of the boiler above the crown sheet.

The front wall 26 of the body is disposed at a 35 relatively steep angle extending downwardly and rearwardly from the crown sheet and provides but a relatively small amount of overhang for this end of the body. The rear wall 27 of the body 40 is disposed at a relatively steep angle, substantially opposite that of the front wall and extends downwardly and forwardly to merge into a rounded corner or nose 27a. That part of the body defining the rear compartment 23 terminates in a stub-like tubular extension 31.

Associated with said rear compartment of the siphon body is a downwardly and forwardly extending inlet neck 32 of substantial length. As shown herein said neck is made from a piece of 50 seamless tubing and the front end of said neck is anchored in a flexible diaphragm 33 preferably flanged up from the top portion of the inner front throat sheet 8. The rear end of said neck is butt welded to the end of the body extension 55 31, above mentioned, as indicated at 34.

The bottom of the front compartment 22 is 60 formed by a rounded and bulged portion 35 disposed above but extending parallel with the neck 32. This bulged bottom, along with parts of the 65 side and front end walls of the siphon body are formed to provide a stub-like inlet neck extension 36 for the front compartment of the body. Said extension receives one end of an inlet neck 37 which extends downwardly and forwardly and as here shown, is bent laterally to be secured in the associated side sheet 6 of the firebox so as to 70 open into the associated side water leg of the boiler. Preferably the inlet neck 37 is made of seamless tubing of the same diameter as the neck 32. When two of such siphons are employed in the firebox, the inlet tube for the front compartment of one siphon preferably opens into one side water leg and the inlet tube for the front compartment of the other siphon opens into the other 75 side water leg.

The bottom of the intermediate compartment 24 is formed by the top portion or part of a substantially circular formation 38. Another portion of said formation merges into a rounded rear corner 39 for the front compartment and 5 said corner blends into the bulged bottom 35 of said compartment. A third portion of said substantially circular formation forms the front end 10 for the rear compartment and merges into the top of the stub-like tubular extension 31. This 15 substantially circular formation, approximately forms a laterally extending opening through the body of the siphon for the passage of the products of combustion. Said circular formation not only bottoms the intermediate compartment 24 but it permits a more practical and flexible union 20 between the neck and the rear end of the siphon body.

Preferably, though not necessarily, the entire 25 body and the tubular extensions 31-36, therefor, are made from an integral sheet, cut to such shape that when folded upon itself by means of a suitable form block, it produces the body and extensions shown. Such an integral structure 30 will have a line of weld extending the length of the front wall, along the bottom of the front compartment, around the substantially circular formation 38 and down along the top of extension 31. Also, a line of welding will follow down along the rear wall 27 to merge into the corner 27a, 35 said line of welding being necessitated because of the removal of certain excess metal from the sheet, that permits the making of the inclined rear wall of the body without a puckering or buckling at said corner. To brace the body of 40 the siphon against internal pressures, the same is transversely staybolted as at 49. Due to the outline shape of the body, less staybolts are required than in a conventional siphon body and this without sacrificing the safety factor.

Instead of making the entire body and the main inlet neck from a single sheet of metal, that part of the body comprising the front compartment may be made from a single sheet of metal and that part of the body comprising the 45 rear compartment and the main inlet neck may be made from a single sheet of metal and the two parts joined by butt welding at about the middle of the intermediate portion 24. While a two part body requires more welding, it has certain advantages in the economy in plate material, due to the use of smaller sheets and to the manner in which the grain of the metal in the two sheets thus used, may be disposed. Which-ever way the siphon is fabricated, that is, either 50 from one or two sheets of metal, the operation of the siphon is the same and the advantages gained over the conventional siphons are likewise 55 the same.

In either instance, the arrangement of the 60 parts is such that the relatively long neck is under compression when in a cold condition as when there is no fire in the firebox. Such compression, of course, is in relation to the body of the siphon and substantially equals the amount 65 of the movement due to expansion, as when the firebox is being fired under service conditions. Under such conditions, when the siphon is under service heat and pressure, only slight stresses, incapable of starting fracture at the inside corners 70 previously mentioned, are present because the force of expansion will return the neck and the upper part of the siphon to their normal positions and thus neutralize the movement thereof.

When the siphons are installed in a firebox, 75

having a so-called long combustion chamber, it may be advisable to provide therein a secondary siphon 41 of a general Y shape formation as appears in Fig. 1. Such a siphon includes a flat 5 hollow staybolted body 42 disposed in the longitudinal median plane of the firebox, the body tapering downwardly at its front and rear to merge into a tubular inlet neck 43. The top end of this secondary siphon opens through the top 10 sheet portion of the combustion chamber and the neck opens through the bottom sheet portion of the said chamber.

When the use of an arch is desired in the firebox, arch tubes 44 may be employed in connection 15 with the necks 32 and which arch tubes are arranged parallel with and in the inclined planes of said necks. This arch may consist of bricks 20 45, the bricks in each longitudinal row all being of the same pattern shape. This avoids the expense of using brick of different pattern shapes in the same longitudinal row. Again, such brick will have a better supporting engagement area upon said necks and arch tubes than is afforded by the bulge on the conventional siphon.

25 By the construction described, more heating surface is provided which induces a greater water evaporating and steaming action and fore and aft circulation of water in the boiler. This is augmented by a further circulation in the side 30 water legs of the boiler to reduce if not entirely eliminate the accumulation of sediment at the bottom of the water legs.

Due to each siphon compartment having a rounded corner at the rear end, the water entering 35 each compartment from its respective neck, tends to keep said corners clean so that tendency of the metal to burn at these points is avoided. Again, the front end of the body may be disposed at an angle nearer the perpendicular so that front 40 end overhang is reduced. Thus dead areas are avoided in the siphon so that the flooding action on the crown sheet is substantially the same throughout the length of the siphon body. By reason of the increased length of neck afforded 45 by the invention, in connection with the use of seamless tubing therefor, greater flexibility is afforded to accommodate siphon movement under the temperature changes met with in the operation of the associated boiler.

50 While in describing the invention, I have referred in detail to the form, arrangement and construction of the various parts thereof, the same is to be considered only in the illustrative sense so that I do not wish to be limited thereto 55 except as may be specifically set forth in the appended claims.

I claim as my invention:

1. In a locomotive boiler firebox, a hollow 60 water steaming and circulating wall including a body, the top of which presents an elongated opening in the crown sheet of the firebox, and a relatively long tubular inlet neck communicating at one end with the water space of the lower part of the boiler and communicating at the 65 other end with the bottom of the body at a point rearward of its front end.

2. In a locomotive boiler firebox, a hollow 70 water steaming and circulating wall including a body, the top of which presents an elongated opening in the crown sheet of the firebox, and a relatively long inlet neck of seamless tubing communicating at one end with the water space of the lower part of the boiler and communicating at the other end with the bottom of the body at a point rearward of its front end.

3. In a locomotive boiler firebox, a hollow 75 water steaming and circulating wall including a body, the top of which presents an elongated opening in the crown sheet of the firebox, and a relatively long tubular inlet neck communicating at one end with the water space of the lower part of the boiler and communicating at its other end with the rear bottom end of the body.

4. In a locomotive boiler firebox, a hollow 10 body, the top of which presents an elongated opening in the crown sheet of the firebox, and a relatively long inlet neck of seamless tubing communicating at one end with the water space of the lower part of the boiler and communicating at its other end with the rear bottom end of the body.

5. In a locomotive boiler firebox, a hollow 15 water steaming and circulating wall including a body having a rear end, the top of which body presents an elongated opening in the crown sheet of the firebox and tubular inlet necks for said wall, each communicating at one end with the water space of the boiler at a point below the crown sheet, one of said necks being connected 20 at its other end to the bottom of the rear end of said body and the other of said necks being connected at its other end to the bottom of said body forward of its rear end.

6. In a locomotive boiler firebox, a hollow 25 water steaming and circulating wall including a body having a rear end, the top of which body presents an elongated opening in the crown sheet of the firebox, and tubular inlet necks for said wall, each communicating at one end with the water space of the boiler at a point below the crown sheet, one of said necks being connected 30 at its other end to the bottom of the rear end of said body and the other of said necks being connected at its other end to the bottom of the body 35 at its front end.

7. In a locomotive boiler firebox, a hollow 40 water steaming and circulating wall including a body formed to provide a plurality of longitudinally spaced compartments which open through the crown sheet by means of a common outlet, the bottoms of certain ones of said compartments being disposed at elevations lower than that of a certain other of said compartments and a plurality of tubular inlet necks for said wall, each 45 communicating at one end with the water space of the boiler below the crown sheet, the other of said necks being connected each to the bottom of said certain ones of said compartments.

8. In a locomotive boiler firebox, a hollow 50 water steaming and circulating wall including a body formed to provide front and rear end compartments, both of which open through the crown sheet, the bottoms of said compartments being disposed at elevations lower than an intermediate 55 portion between said compartments, and a plurality of tubular inlet necks for said wall, each communicating at one end with the water space of the boiler below the crown sheet, one of said necks being connected at its other end with the bottom of one compartment and the other end of the other neck being connected to the bottom of the other compartment.

9. In a locomotive boiler firebox, a hollow 60 water steaming and circulating wall including a body formed to provide front and rear end compartments, both of which open through the crown sheet, the bottoms of said compartments being disposed at elevations lower than an intermediate 65 portion between said compartments, and a plu- 70 75

- 5 rality of inlet necks for said wall, one end of one neck communicating with the front throat of the boiler and one end of the other neck communicating with one of the side water legs of the boiler, the other ends of said necks being connected, each to the bottom of an associated compartment.

10 In a locomotive boiler firebox, a hollow water steaming and circulating wall including a body formed to provide front and rear end compartments, both of which open through the crown sheet, the bottoms of said compartments being disposed at elevations lower than an intermediate portion between said compartments, and a plurality of inlet necks for said wall, one end of one neck communicating with the front throat of the boiler and one end of the other neck communicating with one of the side water legs of the boiler, the other end of the first mentioned neck being connected to the bottom of the rear compartment of the body and the other end of the second mentioned neck being connected to the bottom of the front compartment of the body.

15 11. In a locomotive boiler firebox, a hollow water steaming and circulating wall including a body formed to provide front and rear compartments, each with a tubular extension at its lowermost point, both compartments having a common outlet in the crown sheet, and tubular inlet necks, each connected at one end to an associated compartment extension and each communicating at the other end with boiler water space at a point below the lowest point of the body.

20 12. In a locomotive boiler firebox, a hollow water steaming and circulating element including a body, the top of which opens through and is fixed in the crown sheet so as to move therewith in the expansion and contraction thereof, due to temperature changes, and a tubular inlet neck connected at one end to the body and communicating at its other end with the boiler water space in a plane below the lowest point of said body, said neck being of such length as to be placed under compression by the contraction movement of the body when the same is at a low temperature, to an amount equal to the movement produced in said neck by the expansion movement of the body due to a high temperature.

25 13. In a locomotive boiler firebox, a hollow water steaming and circulating wall including a body formed to provide front and rear end compartments, both of which open through the crown sheet, the bottoms of said compartments being disposed at elevations lower than an intermediate portion between said compartments and each compartment including a rounded corner at its rear end and a downwardly and forwardly extending inlet neck, each neck communicating at one end with the water space of the lower part of the boiler, one of said necks communicating at its other end with the bottom of the rear compartment at the corner thereof and the other of said necks communicating at its other end with the bottom of the front compartment at the front end thereof.

30 14. In a locomotive boiler firebox, a hollow water steaming and circulating wall including a body formed to provide front and rear end compartments, each with a tubular extension at its lowermost point, both compartments having a common outlet in the crown sheet, and tubular inlet necks, each connected at one end to an associated compartment extension and each communicating at the other end with boiler water space at a point below the lowest point of the body.

35 15. In a locomotive boiler firebox, a hollow water steaming and circulating wall including a body, an outwardly extending flange on the top end of the body and connected thereto by a rounded corner fixed in the crown sheet to define the outlet for said body, a tubular inlet neck communicating at one end with the bottom of the body at a point rearward of its front end, and a rounded corner diaphragm in a sheet of the firebox below the crown sheet and in which the other end of said neck is engaged, said neck being of such length as to absorb flexure movement and resulting stresses under temperature changes so as to prevent localization of said stresses in said corner and diaphragm to a degree less than the elastic limits of the metal at these points.

40 16. A thermic siphon for use in a locomotive type of firebox and embodying therein a flat hollow water steaming wall including a body formed to provide front and rear compartments and a third compartment therebetween, all of said compartments having a common outlet at the top, a downwardly and forwardly inclined neck connecting at one end with the bottom end of the rear compartment and the bottom of the front compartment terminating at its front bottom end in a neck extension.

45 17. A thermic siphon for use in a locomotive firebox and embodying therein, a flat hollow water steaming wall including a body formed to provide front and rear compartments, each of a depth different from that of the other and from the depth of a third compartment between the two, all of said compartments having a common outlet at the top, a downwardly and forwardly inclined neck connecting at one end with the bottom end of the rear compartment, the bottom of the front compartment being disposed above a part of said neck and terminating at its front bottom end in a neck extension.

50 18. In combination with the crown sheet of a locomotive boiler firebox, a thermic siphon including a substantially perpendicularly disposed flat hollow body having an upper part opening through said crown sheet and having a bifurcated lower part presenting spaced inlet openings.

55 19. In combination with the crown sheet of a locomotive boiler firebox, a thermic siphon including a substantially perpendicularly disposed flat hollow body having an upper part opening through said crown sheet and having a bifurcated lower part presenting spaced inlet openings, and having neck portions joining said inlet openings.
